LAWRENCE F. BAASH, OF LOS ANGELES, AND WILLIAM H. MAXWELL, OF BEVERLY HILLS, CALIFORNIA

TONGS

Application filed August 25, 1930. Serial No. 477,586.

This invention has to do with tools and has particular reference to tongs useful for handling pipe, casing, and like objects. It is a general object of this invention to provide tongs that are operable to grip an object securely and with great force.

It is an object of the invention to provide a construction that is particularly well suited for embodiment in tongs for handling comparatively large objects such as well casing and well drill pipe, etc.

It is another object of the invention to provide tongs that are of a simple well balanced construction so as to be particularly easy and convenient to operate.

It is another object of the invention to provide tongs in which the means for gripping the pipe or object may be operated directly by the same force or pull that is employed to operate the tool for turning or rotating the pipe.

It is another object of the invention to provide tongs of the character mentioned that are adjustable to grip objects of various diameters or sizes.

It is another object of the invention to provide tongs that are well suited to grip an object, such as a pipe or casing, with great force and may securely grip an object of this character with little danger of crushing or collapsing it.

It is another object of the invention to provide tongs of the character mentioned that embody simple and improved means for gripping the objects to be handled.

It is another object of the invention to provide tongs of the character mentioned that embody but few simple sturdy parts that are capable of withstanding severe strains and hard usage.

It is another object of the invention to provide tongs in which the means for operating the gripping means is in the nature of a lever or toggle means and embodies but two main parts or links.

It is a further object of the invention to provide tongs of the character mentioned in which the operating means is carried by the handle or the lever of the tool and operates to counter-balance the head and the object

gripping means at the active end of the tool.

Other objects and features of our invention will be best and more fully understood from the following detailed description of typical forms and applications of the invention throughout which description reference may be had to the accompanying drawings, in which:

Fig. 1 is a side elevation of one embodiment of the present invention. Fig. 2 is a top or plan view of the tongs. Fig. 3 is a longitudinal detailed sectional view of the tool. Fig. 4 is an enlarged horizontal detailed sectional view of the head portion of the tool and the adjacent parts. Fig. 5 is a vertical or transverse detailed sectional view taken substantially as indicated by line 5-5 on Fig. 4. Fig. 6 is an enlarged vertical detailed sectional view taken as indicated by line 6-6 on Fig. 3. Fig. 7 is an enlarged vertical detailed sectional view taken as indicated by line 7-7 on Fig. 2. Fig. 8 is a longitudinal detailed sectional view of another form of our invention.

The construction provided by the present invention is capable of embodiment in tongs and wrenches for handling various sizes and classes of objects. Throughout the following detailed description the invention will be disclosed in simple forms adapted to handle comparatively large objects such as well casing, drill pipe, etc. It is to be understood that the invention is not to be taken as restricted to the particular forms or application about to be described, but that it is to be taken as including any features or modifications that may fall within the scope of the claims.

The form of the invention illustrated in Figs. 1 to 7 inclusive of the drawings includes, generally, a head 10, a gripping element 11 operable to grip an object extending into the head 10, a lever or handle 12, and means 13 for operating the gripping element 11.

The head 10 is the pipe or work encircling portion of the tool. In accordance with the broader principles of the invention, the head 10 may be constructed and proportioned to accommodate objects of various shapes and sizes. In the particular case illustrated, the

head 10 is designed to embrace or receive objects of round cross sectional configuration, such as a pipe P. The head 10 may include a main or inner part 14 and a gate or outer part 15.

The main or inner part 14 of the head is substantially U-shaped in plan configuration, having two spaced side parts 16 and 17. An opening or recess 18 is provided between the side parts 16 and 17 to hold or receive a pipe P, or the like. The walls of the recess 18 may be curved and the recess may be substantially semi-circular as illustrated throughout the drawings. In the preferred form of the invention the inner part 14 of the head carries the gripping element 11 and an opening or cavity 20 is provided in the inner part of the head for carrying the gripping element. The opening 20 extends a considerable distance around the walls of the recess 18 and extends longitudinally through the side part 17 to its outer end. The upper and lower walls of the opening 20 may be flat and parallel.

The outer or gate part 15 of the head is provided to retain the pipe P in position in the opening 18. The gate or pipe retaining means of the head 10 may be varied considerably in construction. In the particular case illustrated, the gate 15 is in the nature of a single unitary member pivotally carried by the side part 16. A pivot pin 21 may pivotally connect the gate 15 with the side part 16. The outer part or the gate 15 is adapted to close the outer side of the recess 18 and is operable to a position where its free end is adjacent the side part 17. The inner side of the gate 15 is shaped to effectively extend around and engage the objects handled by the tool. In accordance with the invention, the inner side 22 of the gate is curved, so that it is adapted to accommodate and effectively engage pipe and round objects of various diameters. The curvature of the inner side 22 of the gate is such that the gate is adapted to have substantially bearing engagement with pipes and objects varying considerably in size. Grips or dies 23 may be mounted on the inner side of the gate 15 to grip the pipe. The dies 23 may be seated in dovetailed grooves 24 in the gate and may have serrated or roughened outer sides to effectively engage the pipe. A suitable handle 25 may be provided on the outer side of the gate 15.

The invention provides means for releasably connecting the gate 15 with the side part 17 to retain it in the closed position around a pipe P or the like. A suitable latch 26 may be provided to releasably hold the gate 15 in the closed position. The latch 16 may be pivotally carried by the side part 17 so that it is adapted to engage a latch-catch, or lug 27 on the free end of the gate 15. The latch 26 may be yoked or U-shaped having

spaced arms 28. The arms 28 extend into the opening 20 at the outer end of the side part 27 and a pivot pin 29 extends through openings in the side part and the arms 28 to pivotally mount the latch on the side part. 70

A transverse latch part 30 extends transversely between the arms 28 and is adapted to engage or cooperate with the lug 27. The outer portions of the arms 28 may be connected by a suitable handle 31. Means may be provided for yieldingly retaining the latch in cooperative engagement with the lug 27. Leaf springs 32 may be carried by the inner part 14 to engage or bear against the arms 28 to releasably retain the latch in the locked position. 75

The gripping element 11 is mounted in the opening 20 of the head and is operable into gripping or pressure engagement with the pipe P by the means 13. In accordance with the invention the gripping element 11 is in the nature of a pivotally mounted jaw and is preferably a single unitary part. In the particular construction illustrated, the gripping element 11 is pivotally mounted on the pin 29. The upper and lower sides of the element 11 may slidably engage the upper and lower walls of the opening 20 and the outer end of the element 11 may have a tongue 33 to extend between the arms 28 of the latch. The pin 29 extends through an opening 34 in the tongue to pivotally attach the element 11 to the inner part 14 of the head. The gripping element or jaw 11 is provided with a curved inner side 35 to engage or fit around the pipe P when the element is actuated by the means 13. The curvature of the inner side 35 of the element 11 is such that it is adapted to effectively engage or grip pipe of various diameters, that is, it is adapted to engage substantial surfaces or pipes, etc., of various diameters. A die 36 may be mounted on the inner side of the gripping jaw 11. The die 36 may be comparatively long and may have a toothed outer side of substantially the same curvature as the inner side 35 of the element 11. The outer side of the gripping element or jaw 11 may be curved as illustrated throughout the drawings and the inner wall of the opening 20 may be shaped to effectively receive the element so that it is shiftable to a position where it is entirely free of the recess 18. 100

The handle 12 projects from the inner part 14 of the head and is provided to facilitate the handling of the tool and to carry the operating means 13. The lever or handle 12 may be comparatively long and may be integral with the part 14. In accordance with the preferred form of the invention, the handle 12 is bifurcated or provided with a transverse opening 37. The opening 37 extends inwardly from the outer end of the handle 12 and may be comparatively long. The opening 37 is provided to carry the operating 110

means 13 and its upper and lower walls are preferably flat and parallel.

- The means 13 is carried within the opening 37 of the handle and may be operated directly by an operating line, or the like, employed to operate the tool to rotate the pipe P. The means 13 is in the form of a toggle means and includes two pivotally connected links 38 and 39. The links 38 and 39 are arranged within the opening 37 and the link 38 is pivotally attached to the handle 12 adjacent its outer end, while the link 39 is provided to engage and operate the gripping jaw 11. The link 38 is mounted on a pin 40 extending transversely through the opening 37 through a bushing 41. The opening 37 is preferably pivoted adjacent the outer end of the handle, so that the link 38 is pivotally connected with the handle adjacent its outer end. The link 38 may be comparatively short and is provided at its inner end with a recess or socket 42. The outer end of the link 39 is provided with a tongue 43, which extends into the socket 42. A pivot pin 44 extends through the socket 42 and through an opening in the tongue 43^a to pivotally connect the links 38 and 39. In the preferred form of the invention, the inner walls of the socket 42 are curved or rounded and the end of the link 39 is shaped to effectively seat in the socket. The link 39 is an elongated member and extends through a passage or opening 45 in the part 14 to project into the opening 20. The inner end of the link 39 is adapted to engage the outer curved rear side of the gripping jaw 11 and the end of the link may be rounded as illustrated throughout the drawings. The side walls of the opening 45 are curved to permit free movement of the link 39. A guide pin 46 may extend transversely or vertically through the opening 45 to guide the link 39. The pin 46 may extend through an elongated opening 47 in the link. The opening 47 may be formed sufficiently long to permit the desired movement of the link. The links 38 and 39 are mounted and proportioned so that they are buckled to project from one side of the handle 12 when in the unactuated position and upon being urged inward, the link 39 forces the jaw 11 into gripping engagement with the pipe P.
- The links 38 and 39 may be operated in any suitable manner. In practice the links 38 and 39 may be operated by means of the line L employed for turning the tool to rotate or hold the pipe P. The line L may be operatively connected with either of the links 38 or 39 at any suitable point. In the particular case illustrated, a lug 48, having an opening 49 for receiving the line L, projects from one side of the link 38 adjacent the point of pivotal connection of the links. Means may be provided for connecting a return line R with the toggle links. The line R may extend through an opening 51 in a lug 52 project-

ing from the link 38. The opening 51 may be substantially diametrically opposite the opening 49 with reference to the pivotal connection of the links.

In accordance with the invention, means is provided for limiting the inward movement of the links 38 and 39 to prevent them from assuming a position where the axes of the pins 40, 44, and 46 are in direct alignment. The means for limiting the movement of the links may be in the nature of a stop means carried by the link 38. A projection 53 may be provided on the lug 52 and a stop screw 54 may be threaded through the projection. The screw 54 is adapted to engage a side of the handle 12 to limit the inward movement of the links. The screw 54 may be adjusted to provide for the desired movement of the links and a lock nut 55 may be threaded on the screw to set it in any desired position.

The present invention provides means for normally yieldingly holding the links 38 and 39 in the unactuated position and for automatically returning them to their out or unactuated position after the force or pull has been removed from the line L. A leaf spring 56 may be attached to the part 14 of the head and may extend into the opening 37 to engage the link 39. The spring 56 normally yieldingly urges the link 39 outwardly. A helical spring 57 may be provided on the projection 53 around the screw 54 to engage a side of the handle 12. The spring 57 may aid the spring 56 in normally holding the links in an out position and in returning the links to the unactuated position after use. The spring 57 acts to cushion or resist any hammering action there may be between the screw 54 and the handle 12, in the event that the line L is operated suddenly or with great force.

It is a feature of the present invention that the operating means 13 may be adjusted longitudinally of the handle 12 to adapt the tool for handling pipe and objects of various sizes. The link 38 is connected to the handle 12, so that it may be adjusted radially relative to the pipe receiving opening 18 of the head. The bushing 41 directly pivotally carrying the link 38 is in the nature of an eccentric bushing and has an eccentric polygonal opening 60 passing a polygonal portion 61 of the pin 40. The pin 40 has a second polygonal portion 62 projecting from a side of the handle 12. An adjusting handle 63 is mounted on the polygonal portion 62 to facilitate turning of the pin 40 to set the eccentric bushing 41 in various rotative positions. A nut 64 may be screw threaded on the pin 40 to retain the handle 63 in position.

In practice means may be provided for releasably setting the eccentric bushing 41 in different rotative positions. The handle 63 may carry a spring pressed catch or pawl 65 for cooperating with a plurality of spaced notches 66 in the outer end of the handle 12.

The outer end of the handle 12 may be concentrically curved about the axis of the pin 40 and the pawl 65 is adapted to cooperate with or extend into any one of the spaced notches 66 in the end of the handle. A suitable operating lever 67 may be provided on the pawl 65. It will be apparent how the pin 40 may be rotated to adjust the links 38 and 39 longitudinally of the handle through the eccentric bushing 41 and how the links may be set in any desired position by means of the pawl 65.

In the form of the invention illustrated in Fig. 8 of the drawings, the head 10, the gripping element or jaw 11, and the handle 12 may be of the same construction as in the form of the invention described above. In this form of the invention the jaw operating means 13 includes an outer toggle link 38^a and an inner toggle link 39^a. The link 38^a may be of the same formation as the link 38 described above and may be adjustably pivotally mounted on the handle 12 on a pivot pin 40 and eccentric bushing 41. The outer end of the link 39^a is pivotally connected with the link 38^a. The links may be pivotally connected by means of a pin 70 extending through a socket 71 in the link 38^a and an opening 72 in the link 39^a. In this form of the invention a push rod 75 is pivotally connected with the link 39^a. The push rod 75 may be pivotally connected to the link 39^a by means of a pivot pin 76. The rod 75 slidably fits an opening 77 in the inner part 12 of the head 10. The rod 45 is provided to engage the gripping jaw 11 and extends into the opening 20 where it is adapted to engage the curved outer side of the jaw. In the particular case illustrated, the inner end of the rod 75, which engages the jaw 11, is flat. The stop means for limiting the movement of the links 38^a and 39^a and the means for automatically returning the links to their normal position after actuation may be of the same construction as the corresponding means in the form of the invention described above.

It is believed that the utility and practicability of the tool provided by this invention will be readily apparent from the foregoing detailed description. The gate 15 and gripping jaw 11 are shaped so as to be adapted to receive and engage parts of various diameters and so that their pipe engaging faces grip or engage maximum surfaces of the pipe. The gripping jaw 11 is mounted in the head so that it is not subjected to becoming injured or displaced. It is to be noted that the gripping jaw transmits the force applied by the operating means 14 directly to the pipe P without putting much torsional or shearing strain on the pivot pin 29. During operation of the tool the link 39 is urged substantially radially inward toward the pipe P, so that the gripping jaw 11 is clamped directly onto the pipe. It will be apparent how a pull on the

line L, tending to straighten the links 38 and 39, will force the jaw into tight gripping engagement with the pipe, and that the same force or pull may be employed to turn the pipe. The links 38 and 39 may be adjusted through the handle 12 by means of the eccentric bushing 41, so that they are adapted to actuate the gripping element 11 varying distances into the opening 18 to grip pipe of various diameters. It is to be particularly noted that the tool provided by this invention may be embodied in a single sturdy construction that is well balanced. The links 38 and 39 are carried in the handle 12 so that they operate to counter-balance the head 10, and the gripping element 11. The toggle links and the gripping element are carried in openings in the tool, so that they are not subjected to being damaged.

Having described only a typical preferred form of our invention, we do not wish to limit ourselves to the specific details set forth, but wish to reserve to ourselves any changes or variations that may appear to those skilled in the art or fall within the scope of the following claims:

Having described our invention, we claim:

1. A tool of the character described including, a pipe encircling means including an inner part having an opening adapted to receive an object, and a gate adapted to retain an object in the opening, a gripping jaw pivotally carried by the means, a handle on the inner part and means on the handle for operating the jaw into engagement with the object including two pivotally connected toggle links, one of the links being pivoted to the handle adjacent its outer end, the other being adapted to directly engage the jaw, means in the handle for slidably guiding the said other link, and means for adjusting the links longitudinally relative to the jaw to adapt the tool for handling pipe of different diameters.

2. A tool of the character described including, a pipe encircling means including an inner part having an opening adapted to receive an object, and a gate adapted to retain an object in the opening, a gripping jaw pivotally carried in an opening in the inner part and operable to engage the object in the first mentioned opening, a handle projecting from the inner part and toggle means in an opening in the handle for operating the jaw including, two pivotally connected links, one being pivoted to the handle, the other being adapted to pressurally engage the jaw, and a pin carried by the handle and extending through a slot in the said other link for guiding the link.

3. A tool of the character described including, a head adapted to receive an object, a gripping jaw carried by the head operable to engage the object, a handle on the head, means for operating the jaw including two

pivottally connected links in an opening in the handle, one of the links being pivottally mounted on the handle, the other being adapt-
5 ed to engage the jaw, means in the handle opening for slidably guiding the said other link, and means for adjusting the links longitudinally relative to the jaw to adapt the tool for handling pipe of different diameters.

4. A tool of the character described includ-
10 ing, a head adapted to receive an object, a handle on the head, a gripping element pivottally carried by the head, means on the handle for operating the element including two pivottally connected links, one pivottally carried by the handle, the other being adapt-
15 ed to engage the element, and adjustable means for limiting the inward movement of the links.

5. A tool of the character described includ-
20 ing, a head adapted to receive an object, a handle on the head, a gripping element pivottally carried by the head, means on the handle for operating the element including two pivottally connected links, one pivottally carried by the handle, the other being adapt-
25 ed to engage the element, and a screw on one of the links for engaging the handle to limit inward movement of the links.

6. A tool of the character described includ-
30 ing, a head adapted to receive an object, a handle on the head, a gripping element pivottally carried by the head, and means on the handle for operating the element including two pivottally connected links, one link being pivottally mounted on the handle, a push rod slid-
35 able in an opening in the handle and pivottally carried by the other link for engaging the gripping element, and means on a link immediately adjacent the pivotal connection
40 of the links for connecting with an operating line.

7. A tool of the character described includ-
45 ing, a head adapted to receive an object, a handle on the head, a gripping element pivottally carried by the head and means on the handle for operating the element including two pivottally connected links, one link being pivottally mounted on the handle, a push rod pivottally carried by the other link for engag-
50 ing the gripping element, and means on a link immediately adjacent the pivotal connection of the links for connecting with an operating line.

8. A tool of the character described includ-
55 ing, a pipe encircling means, a handle for said means, a pipe gripping jaw on said means and means for actuating the jaw including two pivottally connected toggle links, the outermost link being pivoted to the handle,
60 the innermost link being in direct cooperative engagement with the jaw, and means adjacent the pivotal connection of the links for receiving a laterally extending operating line, the said pivotal connection of the links being lo-
65 cated closer to the outer end of the handle

than to the inner end of the handle whereby a substantial leverage is obtained for turning the tool.

9. A tool of the character described includ-
70 ing, a pipe encircling means, a handle for said means, a pipe gripping jaw on said means and means for actuating the jaw including two pivottally connected toggle links, the outermost link being pivoted to the handle, the innermost link being in direct cooperative engagement with the jaw, and means on one of the links in substantially lateral alignment with the pivotal connection of the links relative to the handle for receiving a member for operating the tool. 75

10. A tool of the character described includ-
75 ing, a pipe encircling means, a handle for said means, a pipe gripping jaw on said means and means for actuating the jaw includ-
80 ing two pivottally connected toggle links, the outermost link being pivoted to the handle, the innermost link being in direct cooperative engagement with the jaw, and means on one of the links in substantially lateral alignment with the pivotal connection of the links relative to the handle for receiving a member for operating the tool, the said pivotal connection of links being located near the outer end of the handle whereby a great 85 effective leverage is obtained for turning the tool. 90

11. A tool of the character described includ-
95 ing, a pipe encircling means, a pivoted pipe gripping jaw carried by the said means, a handle for said means and means for actuating the jaw, including two links, one being pivoted to the handle adjacent its outer end, the other directly operatively engaging the jaw, a pivotal connection between the links located a relatively short distance from the outer end of the handle and including a rounded end part on one link fitting a correspondingly shaped socket in the end of the other link, and a pivot pin carried by the said other link extending through the socket 100 and an opening in the end part of the first mentioned link, and means on one of the links immediately adjacent said pivotal connection for receiving a laterally extending line for operating the tool. 105

In witness that we claim the foregoing we have hereunto subscribed our names this 4th day of August, 1930.

LAWRENCE F. BAASH.

WILLIAM H. MAXWELL.
